UNITED STATES PATENT OFFICE.

STEPHEN R. PARKHURST, OF NEW YORK, N. Y.

IMPROVEMENT IN MACHINERY FOR FEEDING CARDING-ENGINES.

Specification forming part of Letters Patent No. 37,304, dated January 6, 1863.

To all whom it may concern:

Be it known that I, STEPHEN R. PARKHURST, of the city and State of New York, have invented, made, and applied to use a certain new and useful Improvement in Feeding-Tables for Cotton and Woolen Machinery; and I do hereby declare the following to be a full, clear, and exact description of the said invention, reference being had to the annexed drawings, making part of this specification, wherein—

Figure 1 is a vertical section of my said feeding apparatus as applied to a carding machine, and Fig. 2 is a plan of one side of the said feeding-table.

Similar marks of reference denote the same parts.

In carding and other machinery for working cotton, wool, and other fibrous material it is usual to supply a certain amount of the staple upon a given size of belt or apron forming the feeding device in order that the fibrous bat or sliver may be uniform as delivered from the machine; but these feeding belts or aprons are very liable to slip or become obstructed, and the supply of fiber to the machine being lessened or stopped causes the bat or sliver to break or be thinner at the particular part, which deranges the subsequent operations of spinning, &c.

The nature of my said invention consists in a rotary feeding table formed of a cylinder covered with teeth, and on which the material is distributed from a hopper and evened by hand. I also employ a series of toothed rollers in combination with this feeding-table to open the locks of wool previous to their being taken by the cleaning or carding machinery. By this device I am enabled to supply the fibrous material with greater uniformity than by the aprons heretofore employed, and there is less risk of the supply of fiber to the machine being arrested or checked, and the fibers are opened, loosened, and separated by a slow movement, that prevents the injury to the cotton or wool by the pickers, breakers, or cleaners heretofore employed.

In the drawings, *g* is my rotary feeding-table mounted on the shaft *l*, and said table is revolved by means of gearing or any suitable mechanism.

h is an inclined board forming a hopper

against the side of this cylindrical feeding-table, and curved side pieces, *k*, prevent the fibers falling off at the ends of the cylindrical feeding-table. The periphery of this cylindrical rotary feeding-table is divided by means of blocks, pins, or similar devices (shown at *i i i*) whereby the operator or attendant is enabled to know upon what extent of surface a given amount of fiber is to be distributed, and the surface of this feeding-table is clothed with either straight or bent teeth. The cylindrical feeding-table revolves in the direction indicated, and when one of the indicating-blocks *i* has passed the hopper-board *h* the given amount of fibrous material is placed on said board and distributed along the same. The teeth of the table carry up said fibers, and the attendant sees that the mass is evenly distributed between this indicating-block *i* and the next one, which is easily done, as the fibers rest upon said cylindrical feeding-table, and then the operation is repeated by adding the given amount of fibrous material again into the hopper.

l is a roller that presses the fibers to the teeth on the cylindrical table, and this roller may receive an end movement, as it revolves by means of a cam and stationary stud or other suitable device by which the locks or bunches of fibrous material may be spread transversely of the table, causing the mass to be presented to the cleaning or carding machinery in a uniform bat. The fibers might be taken off the feed-table *g* by a pair of feed-rollers to the ordinary carding or cleaning machine, but such device would not fully carry out my invention, by means of which the feed-rollers are dispensed with and their compressing action on the fibers avoided. I provide, therefore, the toothed rollers or cylinders *n* and *o*, which take the fibers from the teeth of the rotary feeding-table, the cylinder *o* entirely cleaning the teeth of said table and being itself cleaned by the cylinder *n*. This operation opens, combs, and partially cards the fibers without liability to cut or break them, as the motion is slow.

a is the ordinary "licker-in" to the carding-cylinder *c* on the shaft *b*, and *d e* represent the usual workers, and *f* the doffer. The opening, combing, and loosening operation on the wool or other fiber is still more promoted by the cylinder *m*, that acts between the cylinder *a*

and n to separate any locks or bunches of fiber and open them; and said cylinder m also removes surplus fibers from the roller l . By these means the fiber is in a proper condition by the time it reaches the portion of the machine adapted to cleaning or carding, so that these operations are performed more effectually than heretofore, and injury to the fiber is avoided, and the usual pickers can thus be dispensed with.

The teeth on the respective rollers and cylinders may be made of wire, or in any usual manner.

The fibers that fall away from the ordinary carding-machines usually accumulate with the dirt beneath the machine. I am enabled to return said fibers to the machine by my feeding-table g , in combination with endless belts p , traveling on rollers q , and carrying cross-rods or scrapers, that draw the fibers along over a screen or netting r to the said cylindrical feeding-table g . The dirt falls away through the netting r , and the fiber is taken by the teeth of the feeding-cylinder g and carried up against the curved guard s and re-entered into the carding-machine, thus effecting a saving of the said fiber and rendering unnecessary the operations now resorted to for

saving this fiber and returning it to the carding-machine.

I do not claim a series of toothed cylinders or rollers acting with the carding-cylinder, as in the patent of Jeptha Dyson, December 6, 1859; but

What I claim, and desire to secure by Letters Patent, is—

1. The cylindrical rotary feeding-table g , to supply the fibrous material to the cleaning or carding machine, substantially as specified.

2. The roller l , in combination with the said cylindrical rotary feeding-table g , for the purposes and as specified.

3. The belts p , screen r , and curved guard s , in combination with the said cylindrical rotary feeding-table g , for the purposes and as specified.

4. A series of toothed cylinders, in combination with the toothed feeding-table, for opening, combing, and separating the fibers, as specified.

In witness whereof I have hereunto set my signature this 10th day of September, 1862.

S. R. PARKHURST.
